UNITED STATES PATENT OFFICE.

PHILLIP JACOB DREHER, OF TOLEDO, OHIO.

OPERATING MEANS FOR RECIPROCATORY ELEMENTS.

1,233,326.

Specification of Letters Patent. Patented July 17, 1917.

Application filed March 9, 1916. Serial No. 83,103.

To all whom it may concern:

Be it known that I, PHILLIP JACOB DREHER, a citizen of the United States, and a resident of Toledo, in the county of Lucas and State of Ohio, have invented a certain new and useful Operating Means for Reciprocating Elements; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates particularly to pneumatically operated instruments, such for instance, as piano-players, organs, orchestrions, or the like, and particularly to power means for operating the air pumps of such instruments.

The object of my invention is the provision of simple and efficient means for mechanically driving the pumps of instruments of the class described, and which is also capable of being easily and quickly disconnected from the pumps to permit a manual operating thereof.

The invention is fully described in the following specification, and while, in its broader aspect, it is capable of embodiment in numerous forms, a preferred embodiment thereof is illustrated in the accompanying drawings, in which—

Figure 1 is a transverse sectional view of an instrument embodying my invention, with parts broken away. Fig. 2 is a section on the line $v-v$ in Fig. 1, with parts broken away; and Figs. 3 and 4 are sections on the lines $w-w$ and $x-x$, respectively, in Fig. 2, one pump bellows being expanded and the other collapsed.

Referring to the drawings, 1 designates the case of an instrument with which my invention is associated, and 2 the pneumatic pumps or bellows thereof, which are customarily arranged within the case. Each of the pumps or bellows 2, two of which are shown in the present instance, is disposed in upright position and has the stationary side 2^a and the movable side 2^b hinged together at their upper ends, as is well understood in the art. The movable side 2^b in each bellows has connection with a foot treadle 3, in the present instance, through the medium of a pair of rods 4.

A spring finger 5 is fixed at one end to the upper end of each bellows side 2^a and has its free end bearing inward against the side 2^b to normally act thereon to effect a compressing or inward collapsing movement thereof. If the bellows or pumps are to be manually operated, it is apparent that this may be accomplished by imparting pumping movements to the treadles 3, as a downward movement of each treadle will force the side 2^b of the associated bellows to its open position against the tension of the spring 5, as shown in Fig. 1, and upon a release of the foot pressure on the treadle, the spring 5 will then impart a collapsing movement to the side 2^b .

The means illustrated in the present instance for mechanically operating the bellows in conjunction with the spring 5 will now be described. Mounted in standards 6, below the stationary side 2^a of the bellows, is a shaft 7 extending lengthwise of the case 1 and carrying a sprocket wheel 8 beneath each bellows, the sprocket wheel being located at one side of a forked bracket 9 that is fixed to the lower end of the stationary side 2^a of each bellows, said bracket preferably having at least one arm thereof forming a bearing for the shaft 7. A bracket 10 is fixed to and projects downward from the lower or free end of the movable side 2^b of each bellows and has its lower end forked and carrying a shaft 11 on which, between the fork arms, is mounted a segmental gear 12. A sprocket wheel 13 is also mounted on the shaft 11 at one side of the fork 10 and in transverse register with the sprocket wheel 8 on the shaft 7. A sprocket chain 14 connects the sprocket wheels 8 and 13 and is intended to communicate rotation from the shaft 7 to the shaft 11 and through it to the gear 12. The length of the chain 14 is sufficient to permit a maximum opening of the bellows 2 with which it is associated.

A rack-bar 15 is pivoted at one end to the bracket 9 of each bellows between the arms of such bracket, as at 16, (Figs. 3 and 4,) and projects therefrom over the segmental gear 12 transversely of its axis and is provided on its lower edge with rack-teeth for meshing with the teeth of said gear. The free end of each rack-bar 15 projects through the fork 10 of the associated bellows and beneath a guide-pin 17 therein, which engages the top edge of the rack-bar and re-

tains the teeth thereof in position to mesh with the teeth of the gear.

It is evident that the rotation of the gear 12 for each bellows being continuous the set 5 of gear teeth thereon will intermittently move into and out of mesh with the teeth on the rack-bar 15. When the bellows is in its normal collapsed position, due to the compressing action of the spring 5 thereon, the 10 segmental set of teeth on the gear 12 will turn into meshing engagement with the set of teeth on the associated rack-bar 15 at the inner end thereof and will cause an opening of the bellows due to the gear traveling out 15 on the rack-bar which is held stationary against endwise movement by reason of its rear end being pivoted to the stationary bracket 9. When the bellows has been opened to its maximum extent by the outward 20 traveling of the gear 12 on the rack-bar, the segmental set of teeth on the gear will pass from engagement with the rack-bar teeth and permit the spring 5 to effect a collapsing of the bellows, such collapsing 25 taking place when the gap in the gear is in register with the rack-bar teeth. When the gear teeth have been moved into coacting relation to the rack-bar they will engage the rack-bar teeth at the inner end of the set, 30 the same as before, and the gear will again travel outward on the rack-bar to effect an opening of the bellows.

In order to retain the sprocket chain 14 taut during the relative inward and outward movements of the shafts 7 and 11, I 35 connect the shafts with a pair of toggle links 18, which are pivotally connected together at their inner ends and adapted to break downward when the bellows is collapsed, as 40 shown in Fig. 4. A yoke 19 is carried in upright position by the connecting pivot or bolt 20 of the toggle links 18 and has its arms extending upward at opposite sides of the chain 14 and connected above the upper 45 portion of the chain by a cross-pin 21 carrying a guide-roller 22, (Fig. 2,) for coacting with the upper side of the chain. The pin or bolt 20 is also provided with a guide-roller 23, which bears against the upper side 50 of the lower half of the sprocket chain. The spacing between the lower surfaces of the guide-rollers 22 and 23 is equal to the spacing between the upper and lower portions of the chain when the shafts 7 and 11 55 are at the maximum limit of their relative outward movements. It is evident that upon an inward relative movement of the shafts 7 and 11 the yoke 19 will be moved downward carrying the upper and lower portions 60 of the chain 14 therewith and preventing slackness from occurring therein, as would otherwise be the case.

A sprocket wheel 24 is mounted on the shaft 10 at one end thereof, in the present 65 instance, and is connected by a chain 25 to

a sprocket wheel 26 on the outer end of a shaft 27, which is mounted in and has its end projecting from a case 28. Mounted on the shaft 27 within the case is a loose gear-wheel 29 and a clutch member 30, the latter 70 being feathered to and axially shiftable on the shaft into and out of clutch engagement with the hub portion of the gear 29. The movements of the clutch member 30 are controlled by a shaft lever 31 extending therefrom to any suitable point of control. The gear 29 meshes with a pinion 32 on a countershaft 33 mounted in the case 28, and this shaft in turn has connection with a motor 34 through the medium of a chain-and-sprocket 80 connection 35.

If it is desired in the use of my invention to operate the bellows or pump from the motor 34, or other suitable drive means, the clutch member 30 is thrown into clutch engagement with the gear 29, thus communicating rotation to the shaft 7 from the motor. The shaft 7 is driven in a direction to drive the chain 14, shaft 11, and segmental gear 12 in the direction indicated by the arrows 85 in Figs. 3 and 4. It is thus evident that the gear 12 will first operate on the rack-bar 15 to cause a maximum opening of the bellows and will then release the rack-bar to permit the spring 5 to effect a collapsing of the 90 bellows, this action being repeated during the operation of the instrument.

If it is desired to operate the bellows by foot power, the clutch 30 is released from engagement with the gear 29, thus disconnecting the bellows operating means from the motor. When the operating means has been thus disconnected the operator can operate with the spring 5 to impart a pumping action to the bellows by operating the 105 treadles 3.

I wish it understood that my invention is not limited to any specific construction, arrangement or form of the parts, as it is capable of numerous modifications without departing from the spirit of the claims.

Having thus described my invention, what I claim as new, and desire to secure by Letters Patent, is—

1. In combination, a movable member, 115 a shaft carried by said member, a stationary rack-bar, a segmental gear adapted when rotated to intermittently mesh with and release said rack-bar, said gear being carried by said shaft, means for normally moving said member to one position, and means for rotating said gear to move said member from normal position.

2. In combination, a movable member, a gear carried by said member, means acting 125 on said member to urge it to one position, a rack-bar anchored against longitudinal movements and positioned to mesh with said gear, a drive shaft, and means connecting said drive shaft and gear for continuously 130

driving the gear during movements of said member whereby the gear intermittently contacts with the rack-bar to cause a movement of the member from normal position and 5 then releases the rack-bar to permit a return of the member to normal position.

3. In combination, a movable member, a transversely movable shaft carried by said member, a stationary shaft, a rack-bar anchored against longitudinal movements and 10 extending transversely of said shafts, a segmental gear mounted on said movable shaft in position to mesh with said rack-bar, means for urging said member to move to 15 normal position, chain-and-sprocket-wheel connection between said shafts to communicate rotation to the movable shaft from said stationary shaft whereby the gear wheel is caused to intermittently engage said rack- 20 bar and move said member from normal position and then release it, and means automatically operable to prevent slack from occurring in the chain when said shafts have 25 relative transverse movements.
4. In combination, a movable member, a transversely movable shaft carried by the movable member, a stationary shaft, a rack-bar anchored against longitudinal movements and 30 extending transversely of said shafts, a segmental gear mounted on said movable shaft in position to mesh with said

rack-bar, means for urging said member to one position, chain-and-sprocket-wheel connection between said shafts to communicate rotation to the movable shaft from said stationary shaft whereby the gear wheel is 35 caused to intermittently engage said rack-bar and impart an opening movement to the movable member and then release it, toggle link connection between said shafts, and 40 chain guiding means carried by said links and movable therewith upon relative inward and outward movements of the shafts to maintain the chain taut during such movements. 45

5. In combination, a movable member, means normally moving said member in one direction, means having connection with said member and operable to successively move it in the opposite direction to said first means and having two transversely spaced shafts, one of which has movements with 50 said member, chain-and-sprocket-wheel connection between said shafts, and means automatically operable by relative transverse 55 movements of said shafts to retain the chain member of said connection taut when the shafts have relative transverse movements.

In testimony whereof I have hereunto signed my name to this specification.

PHILLIP JACOB DREHER.
